UNITED STATES PATENT OFFICE.

WALTER H. PARNELL, JR., OF BROOKLYN, NEW YORK,

SAFETY THIRD RAIL FOR ELECTRIC RAILWAYS.

1,113,680.

Specification of Letters Patent. Patented Oct. 13, 1914.

Application filed May 6, 1907. Serial No. 372,067.

To all whom it may concern:

Be it known that I, WALTER H. PARNELL, Jr., a citizen of the United States, and a resident of the borough of Brooklyn, in the county of Kings and State of New York, have invented certain new and useful Improvements in Safety Third Rails for Electric Railways, of which the following is a specification.

10 This invention relates to a safety third rail with appurtenances for electric railways, and its primary object is the production of a third rail in an electric railway system, which is composed of sections or 15 units of length that are only excited by an electric current, when a vehicle is running adjacent thereto.

Referring to the drawings Figure 1 represents an elevation of the invention with a 20 portion of a car. Fig. 2 shows a section of Fig. 1 on the line 2, 2, Fig. 3 is an enlarged portion of Fig. 2, Fig. 4 shows a section of Fig. 1 on the line 4, 4, Fig. 5 represents the accompanying end of a pair of sections 25 or units of the third rail with their appurtenances, Fig. 6 represents a partial enlarged end view of Fig. 1, and partial enlarged sections of Fig. 1 on the lines 6, 6 and 6^a, 6^a, Fig. 7 shows a section of Fig. 6 on the line 30 7, 7, Fig. 8 is a section of Fig. 6 on the line 8, 8, Fig. 9 represents an enlarged section of Fig. 6 on the line 9, 9, Fig. 10 represents a partial section of Fig. 9 on the line 10, 10.

35 A vehicle 20 is represented with the wheels 21 that are supported on the track 22. A third rail comprising units or sections 23 is located parallel to the track 22. The third rail sections are secured on insulated blocks 24 which latter are carried by the spindles 25 that extend from the plates 26, 27 carried on the cross ties 28.

A bracket 32 extends from the truck 33, and on it is supported a fuse box 34 containing a fuse not shown. A bracket 35 is bolted to the bracket 32, insulating material 36 separating the two brackets. An oscillating arm 37 is pivoted to the bracket 35 by means of the pin 38. A lug 39 extends 50 from the arm 37 to bear against the bracket 35 and a spring 40 extends from the bracket 35 to bear on the arm 37. To the swinging end of the arm 37 is fastened a flexible elliptic spring shaped shoe 41, which latter is

located to bear on the top face of the third 55 rail sections 23.

Movable cover rail-sections 45 of insulating material, preferably of wood, have fastened to their faces hinge plates 46 that are pinned to the arms 47 of the bell cranks 48, 60 by means of the pins 49. The bell cranks 48, are fulcrumed to the brackets 50 having the side plates 51, by means of the pins 52.

Swinging arms 53 are pinned to the hinge plates 54 extending from the movable cover 65 rail 45, the arms 53 being fulcrumed in the brackets 55. The ends of the movable cover rails 45 deflect up as shown with the shoes 56. The ends 57 of the third rail sections 23 deflect downwardly as shown. The bell 70 cranks 48 have each extending from them the flexible or spring arms 58, and to the swinging end of each of the latter is secured a switch plug with the spring jaws 59. The said plug is insulated from the arm 58, 75 and is connected with the insulated wire 60, the latter leading from the insulated feed cable 61.

Within each of the brackets 50 is bolted a supplementary bracket 65, which carries an 80 insulating support 66, for the female member 67 of the switch plug with the jaws 59. A pin 68 holds the member 67 in place. A wire 69 connects the member 67 with the third rail 23.

A wire 70 connects the insulated bracket 35 with the fuse box 34, and from the latter extends a wire 71 to a controller 72 which latter is connected with the motor 73 that drives the vehicle.

To use the invention, as the vehicle reaches the clearance space 74 between an accompanying pair of third rail sections, the shoe 41 is disengaged therefrom and no current is passing through any section 23 of 95 the third rail. As the shoe approaches the entering end of the third rail section beyond the said clearance space, the movable rail section 45 that accompanies the third rail is raised and allows the shoe to enter 100 between said section 45 and its third rail. When the rail section 45 is raised, the switch plug with the jaws 59 makes contact with the female member 67, and closes the electric circuit between the feed wire 61 and 105 the third rail section. From the latter the current passes through the shoes 41, arm 37, bracket 35 and wires 70 and 71 to the con-

- troller 72 in the vehicle 20. The switch plug by reason of its construction with the two spring jaws 59 allows good contact with its female member 67, and as the bell crank 48 is oscillating, the jaws 59 are moving relatively to their female member, and consequently the contact faces of the switches are rubbing on each other, and constitute a self cleaning switch.
- 10 It will be noted that when the shoe is not engaging the movable cover rail sections 45, the said cover will protect the third rail sections 23 from dirt, snow and the like, keeping them clean for contact with said shoe. The brackets 50 protect the electric switches, and the side plates 51 being removable allow the adjustment of said switches with their appurtenances.
- Having described my invention I claim:
- 20 1. In an electric railway system the combination of a vehicle and third rail sections, bell cranks fulcrumed adjacent to the third rail sections, movable cover rails extending from one of the arms of each bell crank, electric switches for the third rail sections, each electric switch having a switch plug extending from the other arm of the bell crank, a main feed wire in circuit with said plug, said switch also comprising a female member for the switch plug, an electric conductor connecting said female member with the third rail, a shoe extending from the vehicle and arranged to bear on the third rail sections under the movable cover rails.
- 25 2. In an electric railway system the combination of a vehicle and third rail sections, the accompanying ends of each pair of the latter separated from each other, bell cranks fulcrumed adjacent to the third rail sections, cover rails of insulating material hinged to one arm of each bell crank, electric switches for the third rail sections, each electric switch having a switch plug with spring jaws extending from the other arm of the bell crank, a main feed wire in circuit with said plug, said switch also comprising a female member for the switch plug, a main feed wire in circuit with said plug, an electric insulated conductor connecting the female member of the switch with the third rail, a bracket extending from the vehicle, an arm pivoted to the bracket, a shoe supported on the swinging end of the arm and located to bear on the third rail sections under the said cover rails, and an electric motor in the vehicle in circuit with said shoe.
- 30 3. In an electric railway system the combination of a vehicle and third rail sections, the accompanying ends of each pair of the latter deflected downwardly and separated from each other, bell cranks fulcrumed adjacent to the third rail sections, cover rails hinged to one arm of each bell crank, electric switches for each third rail section,

each electric switch having a switch plug extending from the other arm of the bell crank, a main feed wire in circuit with said plug, said switch also comprising a female member for the switch plug, an electric conductor connecting said female member with one of the third rail sections, and a flexible shoe extending from the vehicle arranged to bear on the third rail sections under the cover rails.

4. In an electric railway system the combination of a vehicle and third rail sections, the accompanying ends of each pair of the latter deflected downwardly and separated from each other, bell cranks fulcrumed adjacent to the third rail sections, cover rails hinged to one arm of each bell crank, electric switches for each third rail section, each having a switch plug extending from the other arm of the bell crank, a main feed wire in circuit with said plug, said switch also comprising a female member for the switch plug, an electric conductor connecting said female member with one of the third rail sections, a bracket extending from the vehicle, an oscillating arm pivoted to the bracket, a flexible shoe extending from the arm and arranged to bear on the third rail sections under the cover rails.

5. In an electric railway system the combination of a vehicle and third rail sections, bell cranks fulcrumed adjacent to the third rail sections, swinging arms located between the bell cranks, cover rails hinged to one arm of each bell crank and to the said swinging arms, electric switches of each third rail section, a flexible arm for each bell crank, spring jaws one for each electric switch extending from the flexible arm of a bell crank, a main feed wire in circuit with said jaws, an electric conductor extending from each electric switch to its accompanying third rail section, an oscillating arm extending from the vehicle and a flexible elliptic spring shaped shoe extending from the oscillating arm, the shoe located to bear on the third rail sections under the cover rails.

6. In an electric railway system the combination of a vehicle, tracks for the vehicle, spindles adjacent to the tracks, insulated blocks on the spindles, third rail sections secured to the blocks, the adjacent ends of each pair of third rail sections separated from each other, brackets adjacent to the sections, a bell crank fulcrumed to the inside of each bracket, cover rails hinged to one arm of each bell crank, the adjacent ends of each pair of cover rails separated from each other, electric switches for each third rail section one under each bracket, a spring arm extending from each bell crank, spring jaws extending from each spring arm for each electric switch, a main feed wire in circuit with the spring jaws, an electric conductor extending from each elec-

tric switch to its accompanying third rail section, a flexible shoe extending from the vehicle and arranged to bear on the third rail sections under the cover rails and an electric motor on the vehicle in circuit with said shoe.

5 Signed at the borough of Manhattan in

the county of New York and State of New York this 29th day of April, A. D. 1907.
